UNITED STATES PATENT OFFICE.

CARL ENGBERG, OF ST. JOSEPH, MICHIGAN, ASSIGNOR TO ABEL W. WELLS
AND JOHN HIGMAN, OF ST. JOSEPH, MICHIGAN.

MACHINE FOR MAKING BASKET-COVERS.

SPECIFICATION forming part of Letters Patent No. 699,463, dated May 6, 1902.

Application filed October 31, 1901. Serial No. 80,643. (No model.)

To all whom it may concern:

Be it known that I, CARL ENGBERG, a citizen of the United States, and a resident of St. Joseph, in the county of Berrien and State 5 of Michigan, have invented a new and Improved Machine for Making Basket-Covers, of which the following is a full, clear, and exact description.

This invention relates to a machine for making covers for baskets and other receptacles, and it involves certain novel mechanism concerning the holder for the work and the means for rotating and otherwise actuating said holder as it coacts with the stapling or nail- 15 ing device.

This specification is a specific description of one form of the invention, while the claims are definitions of the actual scope thereof.

Reference is to be had to the accompanying 20 drawings, forming a part of this specification, in which similar characters of reference indicate corresponding parts in all the views.

Figure 1 is a perspective view of the invention. Fig. 2 is a front elevation with one of 25 the work-holders in section. Fig. 3 is a vertical section taken along the drive-shaft of the machine. Fig. 4 is a horizontal section on the line 4 4 of Fig. 2. Fig. 5 is a view of a cover made by the machine, and Fig. 6 is 30 a sectional detail of the work-holder on the line 6 6 in Fig. 2.

6 indicates the base of the machine, on which are erected two stanchions 7, carrying rigidly at their upper ends a table 8. This 35 table is provided with two vertically-disposed bosses 9, carried rigidly thereby and through which the shafts 10, respectively, run. These shafts carry each a horizontally-disposed disk 11, forming part of the work-holder. this disk 40 having parallel ribs 12 thereon, which constitute guides for laying the parallel slats of the cover over the holder 11.

14 indicates catches for holding in place the cross-slat which forms part of the cover, 45 and 14^a indicates a spring for holding the catch raised or lowered.

Fig. 5 shows the cover, and this comprises a rim or hoop 15, parallel slats 16, and a cross-slat 17. The ribs 12 are separated to form a 50 diametrically-extending passage across the top of the holder 11, in which the cross-slat 17 is received. Carried to slide radially on

the underside of each form 11 are four clamps 18. (See Figs. 2 and 6.) These clamps have rods 19 connected thereto, and the said rods 55 are in turn joined to levers 20, fulcrumed on collars 23, fastened to the shafts 10. Sliding on each boss 9 is a cone 21, these cones working with the levers 20, which spread apart at the lower ends thereof when the cones are 60 raised. This movement of the levers 20 will draw the clamps 18 inward and cause the hoop 15 of the cover (see Fig. 5) to be held firmly between the holder 11 and the clamps. The cones 21 are actuated by cranked shafts 65 22, which are rockably mounted in the table 8 and so arranged that by throwing upward the bent front portions of these cranked shafts 22 the cones 21 will be thrown upward and the levers 20 actuated to clamp the hoops 70 15 between the holders and the corresponding clamps 18.

56 indicates a retractile spring which is connected to the shafts 22, whereby to hold the cones 21 raised. The cones 21 may be 75 either fast or loose on the bosses 9. If the cones are fast on the bosses, the levers 20 must turn around the cones during the action of the machine, as will be hereinafter fully described; but if the cones are loose on the 80 bosses 9 they may be connected with the parts 11 and 23, so as to turn therewith.

The shafts 10 carry at their lower ends ratchet-wheels 24, these wheels being fastened to the shafts, so as to impart a step-by-step rotary movement thereto.

25 indicates a double pawl which is carried on a shaft or rod 26 to move forward and back therewith. This rod 26 is mounted under the table 8 of the machine. The pawl 25 has 90 springs 27 connected thereto, and these springs are in turn attached to arms 28, fastened to a lever 29, which is mounted fast on a hollow column or sleeve 30, carried to turn in a vertical tubular extension 31, preferably 95 formed integral with the table 8. The pawl 25 lies between the ratchet-wheels 24, and by throwing the lever 29 from one position to the other the pawl 25 may be made to engage either of the ratchet-wheels 24. This movement of the lever 29 also turns the sleeve or column 30, for a purpose that will hereinafter appear. The shaft or rod 26 is mounted loosely 100 in the framing of the machine just below the

table 8 and is pressed backward by a spring 32. The rod 26 is moved forward through the action of an arm 33, against which works a cam 34, carried to turn around the axis of the 5 drive-shaft 35 of the machine. Now it will be clear that as the cam 34 works against the arm 33 it imparts, in conjunction with the spring 32, a reciprocal movement to the rod 26. This works the pawl 25 back and forth, 10 and one of the ratchet-wheels 24, according to which is engaged by the pawl 25, will be given a step-by-step rotation.

The cam 34 is carried on a sleeve 36, loosely encircling the shaft 35 and formed with a 15 clutch member 37 and an eccentric 38. The clutch member 37 works with a clutch member 39, splined on the shaft 35, and the eccentric 38 has a strap 40 mounted thereon. The clutch member 39 is actuated by a bent and 20 split lever 41, fulcrumed on a link 42, mounted on one of the stanchions 7 of the frame. This bent lever 41 projects through said stanchion at the front of the machine and is connected by a link 43 with the lever 29. Now it is clear 25 that as this lever 29 is thrown horizontally from one side to another the link 43 will be actuated to throw the lever 41. When the lever 29 is in the intermediate position, (shown in Figs. 2 and 3,) the clutch member 39 will 30 be disengaged from the member 37; but when the lever 29 is thrown to the right or left, as indicated by the dotted lines in Fig. 2, the bent lever 41 will be actuated to connect together the clutch members 39 and 37, thus 35 turning with the shaft 35 the parts 38, 36, and 34.

44 indicates two latches, which are mounted at the sides of the machine and are adapted to be engaged by the lever 29 to hold the 40 lever either to the right or to the left, according as it may be thrown. These latches 44 have tails respectively extending adjacent to the peripheries of the ratchet-wheels 24, and the ratchet-wheels have outwardly-projecting 45 spurs 45, which as the ratchet-wheels turn run into engagement with the tails of the latches 44 and throw said latches into released position. Therefore when the lever 29 is thrown to one side it throws the pawl 25 50 into engagement with the ratchet-wheel 24, toward which the lever is thrown. It also connects the clutch members 37 and 39 and causes the cam 34 to turn with the shaft 35, thus imparting a reciprocal movement to the 55 pawl 25. This movement causes the ratchet-wheel above referred to to turn with a step-by-step movement around the axis of the shaft 10. This movement is continued until the spur 45 of the ratchet-wheel in question 60 runs under the tail of the latch 44 adjacent to the ratchet-wheel. This spur 45 disengages the latch 44 from the lever 29, and the lever then returns to its intermediate or inactive position.

65 In order to prevent idle movement of the ratchet-wheels 24, I provide friction-blocks 46. (See Figs. 1 and 4.) These blocks 46 bear

slidably on top of the ratchet-wheels and are carried, respectively, by bent levers 47, mounted to rock in the rear stanchion 7 of the frame. 70 The lower ends of the levers 47 are drawn tightly together by a retractile spring 48. The friction-blocks 46 being thus held on the ratchet-wheels 24 allow the ratchet-wheels such movement as may be imparted to them 75 by the positive action of the pawl 25, but prevent the ratchet-wheels from moving by momentum or the jarring of the machine.

The hoop 15 and the slats 16 and 17 of the top being placed on the holder 11 in the 80 proper position, as described, and the lever 29 thrown so as to cause the rotation of one of the holders, the staples are driven into the slats so as to fasten them to the hoop. The staples are driven by a stapling mechanism 85 which may be of any form desired. The drawings show the outline of this mechanism, 49 indicating the stationary part, which is carried on the sleeve or column 30, and 50 indicates the reciprocal part, which is carried 90 loosely on a rod 51, arranged to slide through the sleeve 30 and connected by an arm 52 with the strap 40 of the eccentric 38.

55 indicates a spring which throws downward the rod 51. 95

54 indicates an arm carrying the wire-reel of the stapling device. As the lever 29 is thrown to adjust the pawl 25 it also turns the stapling mechanism, so that it will lie over the work-holder toward which the lever 29 is thrown. It will be seen that when the lever 29 is thrown to the right it starts the movement of the right-hand holder. It also throws the stapling device to the right, and as the shaft 35 drives the eccentric 38 the movable 105 part 50 of the stapling mechanism is operated, thus driving the staples through the slats into the hoop. The work is given a step-by-step movement, thus presenting it at various points around the periphery of the top or 110 cover to the action of the stapling device. When the work has been given a complete turn, the projection 45 of the ratchet-wheel 24, which is rotating, will strike the corresponding latch 44 and throw the machine out 115 of action. While one of the holders contains the work which is being operated on by the stapling device the attendant may be engaged in placing the work in the other holder, and as the operation of the first holder ceases 120 the attendant should throw the lever 29 toward the second-named holder, thus starting the operation thereof.

Various changes in the form, proportions, and minor details of my invention may be resorted to without departing from the spirit and scope of my invention. Hence I consider myself entitled to all such variations as may lie within the scope of my claims.

Having thus described my invention, I 130 claim as new and desire to secure by Letters Patent—

1. The combination of a work form or holder, means for imparting a step-by-step movement

thereto, and a stapling device coacting with the work-holder, said work-holder comprising a circular body or form, parallel ribs on the top thereof, and a clamp or clamps working 5 against the periphery of the form.

2. The combination of a work form or holder, means for imparting a step-by-step movement thereto, a stapling device coacting with the work-holder, said work-holder comprising a 10 circular body or form, parallel ribs on the top thereof, a clamp or clamps working against the periphery of the form, the parallel ribs being separated by an open space running across them, and a catch located at said space, 15 for the purpose specified.

3. The combination of a work form or holder, means for imparting a step-by-step movement thereto, a stapling device coacting with the work-holder, the work-holder comprising a 20 body or form, a clamp working against the body, a lever connected to the clamp, a tapering member acting on the lever, for the purpose specified, and means for actuating the said tapering member.

25 4. The combination with a frame, of a boss carried thereon, a shaft arranged to turn thereon, a means for driving the shaft, a work-form carried by the shaft, a clamp working with and carried by the form, a lever connected with the clamp, a tapered member 30 slidable on the boss to engage and throw the lever, and means for actuating the said tapered member.

5. The combination of a rotary shaft, a work-form carried thereby, a ratchet-wheel fixed to the shaft, a pawl, means actuating the pawl to impart a step-by-step movement to the ratchet-wheel, and a friction device coacting with the ratchet-wheel and its connected part 40 to prevent idle movement thereof, said friction device comprising a block, a cranked rock-shaft whereon it is carried, and a spring pressing the rock-shaft.

6. The combination with two work forms or 45 holders, of a means movable into engagement with one or the other to impart a step-by-step movement thereto, and a stapling device in connection with said means to be shifted in accord therewith.

50 7. The combination of two work forms or holders, a reciprocal device adapted to impart a step-by-step rotary movement to one or the other of the work-holders, a lever connected with said reciprocal device to throw it to the 55 adjustment desired, and a stapling device connected with the lever, to be shifted upon the movement thereof.

8. The combination of two work forms or 60 holders operative with a step-by-step rotary movement, a ratchet-wheel in connection with each, a reciprocally-driven member, a pawl pivotally carried on said member, and means for throwing the pawl into engagement with one ratchet-wheel or the other.

9. The combination of two work forms or 65 holders operative with a step-by-step rotary movement, a ratchet-wheel in connection with each, a reciprocally-driven member, a pawl pivotally carried on said member, means for throwing the pawl into engagement with one 70 ratchet-wheel or the other, and a stapling device connected with said means for throwing the pawl, whereby to be adjusted in unison with the pawl.

10. The combination of two work forms or 75 holders operative with a step-by-step rotary movement, a ratchet-wheel in connection with each, a reciprocally-driven member, a pawl pivotally carried on said member, a lever connected with the pawl to throw it into engagement with one ratchet-wheel or the other, a member mounted to turn and forming the fulcrum of the lever, and a stapling device connected with said turning member.

11. The combination with two work forms or 80 holders, of a means movable into engagement with one or the other to impart a step-by-step movement thereto, a stapling device in connection with said means, to be adjusted in accord therewith, an operating-lever for the said 85 means, a gearing for driving the said means, said gearing including a clutch, and a connection between the clutch and operating-lever.

12. The combination of two work forms or 90 holders, a means for imparting a step-by-step 95 movement to either of the work-holders, a hollow column mounted to turn, a lever connected thereto and to said means for imparting movement to the work-holders, a stapling device carried by the column, an operating-rod 100 running through the column to actuate the stapling device, a drive-shaft, a clutch coacting therewith, a connection between the lever and the clutch to actuate the latter, and devices actuated from the drive-shaft and controlled by the clutch, said devices respectively 105 driving the means for imparting movement to the work-holders and the said operating-rod.

13. The combination of two work-form holders, a means movable into engagement with 110 either one or the other to impart a step-by-step movement thereto, and a stapling device capable of working with either one of the work-holders.

In testimony whereof I have signed my 115 name to this specification in the presence of two subscribing witnesses.

CARL ENGBERG.
